PROCESS AND APPARATUS FOR SURFACING
PLATE GLASSFrancis V. Wilhelm and Thomas K. Gregorius,
Creighton, Pa., assignors to Pittsburgh Plate
Glass Company, a corporation of Pennsylvania

Application September 1, 1933, Serial No. 687,771

5 Claims. (Cl. 51—240)

The invention relates to a process and apparatus for surfacing plate glass and particularly to a method of maintaining the tops of the cars or tables which pass beneath the grinding and polishing runners in the straight away surfacing operation in a true horizontal plane. During the polishing operation, considerable heat is developed due to the relatively high frictional contact between the polishing pads and the glass. 10 This heat is transmitted to the metal plates constituting the tops of the tables and causes them to bulge up slightly at the center so that the surfaces which carry the glass are no longer in a true horizontal plane. This condition corrects itself in part during the return of the tables to the grinding end of the line after the polishing operation, but some convexity still remains, and when the table is again passed beneath the grinding runners (carrying thereon a new plate of 15 glass or one which has been surfaced only on one side) the glass plate is reduced to uneven thickness, being ground thinner along the middle portion than along the edges at the sides of the table. The object of the present invention is 20 to overcome this difficulty by eliminating the bulging or warping of the table tops between successive surfacing operations, so that the table tops are perfectly true and flat during each grinding operation. Certain embodiments of the invention are illustrated in the accompanying drawings, wherein:

Figs. 1, 2 and 3 illustrate one form of the apparatus, Fig. 1 being a longitudinal section, Fig. 2 a transverse section on the line II—II of 35 Fig. 1, and Fig. 3 a partial plan view. And Figs. 4, 5, 6 and 7 illustrate modifications, the views being in all cases transverse sections similar to that of Fig. 2.

Referring to the construction of Figs. 1, 2, and 40 3, 1 is one of a series of glass surfacing tables, to whose upper side sheets of glass are secured by means of plaster of par's, and which are carried beneath a series of grinding and polishing machines, not shown; 2 is the return track along 45 which the cars are carried by any suitable means from one end of the grinding system to the other. As shown, the cars are provided on under sides with racks 3, which are engaged by suitable driving means 4 (Fig. 2) for moving the train of 50 cars continuously along the track 2.

Located above the line of travel of the cars are a series of sprays 5 connected to a transverse pipe 6, and beneath the line of travel of the cars are a series of sprays 7 connected to the pipes 55 8 and 9. These pipes are all connected to a water

supply pipe 10, so that when the control valve for the pipe 10 is open, the upper and lower surfaces of the plate 11, which constitutes the top of the car or table, are sprayed with water. The valve 12 on the pipe 10 is operated from a 66 solenoid whose coil is supplied by leads 13, 13, and one of these leads is provided with a switch 14 having a roller 15 bearing on the top of the table. While the tables are passing beneath the spraying apparatus, the switch 14 is held in 65 closed position so that the valve 12 is held open. When the tables pass the switch 14, it opens and the valve 12 is closed, thus cutting off the supply of water and preventing wastage. In order to dry the tables, conduits 16 and 17 are provided extending transversely of the tables. These pipes are perforated on their sides next to the table and are supplied with air under pressure.

The apparatus as above described provides a means for cooling the table tops 11 rapidly so that 75 any bulge therein incident to the heating effect of the polishers is removed and the upper surface of the top 11 returns to its true horizontal plane before the table is again passed beneath the grinding and polishing machines.

Fig. 4 illustrates a modification in which the cars 1 are passed through a chamber 18 provided with a series of refrigerating pipes 19 in its upper portion and a plurality of steam pipes 20 lying at a level below the table tops 11. By this means, 85 the upper surfaces of the tables are cooled and their lower surfaces are heated, the amount of cooling and heating being so regulated that the plates 11 are brought to a substantially uniform temperature throughout during the passage of 90 the cars through the chamber 18.

Fig. 5 illustrates a further modification in which the cars 1 are passed through a heat modifying chamber 21. In this case, heat is supplied beneath the table tops by means of the gas burners 22 connected to suitable supply pipes 23. By this means, the lower sides of the table tops are brought to substantially the same temperature as the upper sides so that any bulge in the tops is removed. In some cases, the heat applied by 95 the burners may be somewhat in excess of that required, and in that case the series of electric heaters 24 carried by the top of the chamber are used to give the additional heat necessary in the tops of the tables. The heaters are supplied by 100 current from the leads 24.

Fig. 6 illustrates a further modification in which the cooling of the tables is accomplished by means of the air jets 24' supplied from the casings 25, 25. Air is forced into the casing from the blower 26 110

through the conduit 27, the fan being operated by the electric motor 28. In order to increase the cooling effect of the air, refrigerating pipes 29 are provided at the entrance end of the casings 25, 25. The cooling effect may also be accentuated by applying some water to the casing 25, 25, this being accomplished by means of the mist sprayers 30, 30 supplied from the pipes 31, 31.

Fig. 7 illustrates still another method of cooling the top plates 11 of the cars as they pass along the track 2. The cooling means in this instance comprises an endless belt made up of the metal plates 32, 32 carried upon sprocket chains 33, 33 passing around suitable sprockets and arranged 15 so that as the cars pass beneath the endless belt, the plates 32 rest upon the tops of the tables and exert a cooling effect thereon. The plates 32 constituting the endless belt are preferably cooled by a series of refrigerating pipes 34 located just 20 above the top flight of the belt. This belt may be driven or may be moved merely by contact of the lower flight with the tops of the moving tables. The cooling effect is such that the top 25 surfaces of the plates 11 constituting the table tops are brought to substantially the same temperature as the lower sides of these plates so that the plates return to a true horizontal plane.

What we claim is:

1. A process of treating glass grinding and polishing tables between successive operation which 30 consists in subjecting the tops of the tables to temperature modifying means tending to bring the upper and lower faces of such tops to the same temperature and thus restore the flatness 35 of the tops.

2. A process of treating glass grinding and polishing tables between successive operation which consists in subjecting the upper faces of the tops thereof to cooling means tending to restore such upper faces of the tables to a temperature approximating that of the lower faces and thus restore the flatness of the tops. 80

3. A process of treating glass grinding and polishing tables between successive operation which consists in subjecting the lower faces of the tops thereof to heating means tending to bring such lower faces of the tops to a temperature approximating that of the upper faces and thus restore the flatness of the tops. 85

4. A process of treating glass grinding and polishing tables between successive operation which consists in subjecting the upper faces of the tops thereof to cooling means and the lower faces thereof to heating means thereby tending to bring the upper faces to a temperature approximating that of the lower faces and thus restore the flatness of the tops. 90

5. In combination in glass surfacing apparatus including tables for carrying glass plates beneath grinding and polishing runners and a return track 100 for the tables, a chamber through which the track extends, refrigerating means in said chamber just above the level of the table tops, and heating means in the chamber below the level of the table tops, said refrigerating means in connection with the heating means tending to bring the upper and lower faces of the tables to approximately the same temperature. 105
